CLAIM

The ornamental design for an inflatable camper tent, as shown and described.

DESCRIPTION

FIG. 1 is a top front perspective view of an inflatable camper tent, showing my new design;

FIG. 2 is a front elevation view of FIG. 1;

FIG. 3 is a rear elevation view of FIG. 1;

FIG. 4 is a top plan view of FIG. 1;

FIG. 5 is a bottom plan view of FIG. 1; and,

FIG. 6 is a right side elevation view of FIG. 1, the left side elevation view being a mirror image thereof.

The broken lines shown in the drawings depict portions of the inflatable camper tent that form no part of the claimed design.
